NECKTIE

William Blumberg, Baltimore, Md.

Application August 17, 1956, Serial No. 42,650

Term of patent 3½ years

(Cl. D3—16)

Fig. 1 is a perspective view of a necktie showing my design;

Fig. 2 is an enlarged fragmentary view thereof showing the bottom front portion;

Fig. 3 is a side elevational view thereof; and

Fig. 4 is a fragmentary rear view thereof, the rest of the underside of the necktie being plain and unornamented.

The essential features of the design reside in the portions shown in solid lines on the drawing.

What is claimed is:

The ornamental design for a necktie, as shown and described.
